HOLDER FOR COOKING RANGE
ACCESSORIESHarold H. Ring, Rockford, Ill., assignor to Geo. D.
Roper Corporation, Rockford, Ill., a corporation
of Illinois

Application September 22, 1941, Serial No. 411,833

8 Claims. (Cl. 211—86)

This invention relates to cooking ranges and is more particularly concerned with an improved holder for a timer and condiment shakers, so that these may be located conveniently and safely on the cooking top or on top of the back rail.

The principal object of my invention is to provide a simple and inexpensive holder which can be stamped from a single piece of sheet metal and which is substantially completely concealed by the timer and condiment shakers when set thereon.

Another object consists in the provision of a bracket of the kind mentioned which has a retaining lug provided thereon in such a way that the bracket may be fastened interchangeably on top of the back rail or on the cooking top on different styles of ranges.

Still another object consists in the provision of a bracket of the kind mentioned having aligned elongated retainer ribs provided thereon in longitudinally spaced relation, of such length and so spaced in relation to grooves provided in the bodies of the timer and condiment shakers that a pair of shakers may be placed on the bracket in end to end relationship and securely held against displacement, or the same bracket may be used interchangeably with a timer and two shakers placed on opposite sides of the timer, the bracket serving to hold the three pieces just as securely as the two pieces.

The invention is illustrated in the accompanying drawings, in which—

Fig. 1 is a perspective view of the cooking top portion of a range having the back rail equipped with a holder made in accordance with my invention for support of a timer and a pair of salt and pepper shakers;

Fig. 2 is a similar view of another range, showing the same holder holding the pair of shakers alone;

Fig. 3 is a perspective view of the holder removed from the range and shown substantially full size;

Fig. 4 is a perspective view of one of the shakers shown substantially full size and looking at the back thereof so as to show the grooves provided in the body of the shaker for cooperation with the ribs on the holder;

Fig. 5 is a vertical sectional detail on the line 5—5 of Fig. 2 showing how the holder bracket is fastened to the top of the back rail;

Fig. 6 is a perspective view of the cooking top portion of another range showing the holder mounted on the cooking top portion;

Fig. 7 is a vertical sectional detail on the line 7—7 of Fig. 6 showing how the lug of the holder

bracket is fastened between the back rail and the cooking top, and

Figs. 8 and 9 are views of a condiment and timer set and a condiment set, respectively, partly in front elevation and partly in vertical section on the line 8—8 of Fig. 7, so as to illustrate the interengagement of the ribs on the holder bracket in the grooves in the bodies of the timer and shakers.

The same reference numerals are applied to corresponding parts throughout the views.

Referring first to Fig. 3, the reference numeral 10 designates the holder of my invention, which is usable interchangeably with a pair of condiment shakers, like those shown at 11 and 12 in Figs. 2, 6, and 9, or with a three-piece set consisting of shakers 11 and 12 together with a timer 13, as shown in Figs. 1 and 8. In a range like that shown at 14 and 14' in Figs. 1 and 2, where the cooking tops 15 and 15' have integral upwardly projecting rear portions 16 for support of the back rail 17, the holder 10 is arranged to be mounted on top of the back rail. On still another style of range, like that shown at 18 in Fig. 6, where the cooking top 19 is entirely independent of the back rail 20, and the back rail is arranged to be fastened by its lower edge portion to the downwardly projecting rear flange 21 on the cooking top, as by means of screws 22, only one of which appears in Figs. 7, 8, and 9, the holder 10, as will more clearly appear hereafter, is adapted to be mounted directly on the cooking top, as shown in Figs. 6 and 7. In that style of range, shown in Fig. 6, the holder 10 may, if desired, be placed on top of the back rail 20, similarly as shown in Figs. 1, 2, and 5.

The holder 10 consists of a one-piece sheet metal bracket formed to provide an elongated shelf portion 23 having upwardly projecting retaining ears 24 and 25 on the back thereof at opposite ends, and having a downwardly projecting attachment lug 26 on the back thereof between and in rearwardly offset relation to the ears 24 and 25. The lug 26 has a vertical slot 27 provided therein opening from the lower edge thereof and adapted to receive therein a screw, like that shown at 28 in Fig. 7 or like that shown at 28 in Fig. 5, in the fastening of the holder bracket to the range. The thin sheet metal lug 26 can be entered easily between the back rail 20 and the cooking top 19 when one or more of its fastening screws 22 are loosened slightly, and then after one of the screws has been entered in the slot 27 and the screws are tightened again the holder is held securely. Where the holder is fastened onto the top of the back

rail 17 or 20, as shown in Fig. 5, a single screw 28 entered in a hole in the downwardly projecting flange 29 on the top of the back rail serves to fasten the holder securely enough, the screw in this case also being entered in the slot 27.

The front edge portion of the holder bracket 10 is formed to provide three aligned, elongated, upwardly projecting hollow ribs 29, 31, and 32 substantially of C-shaped cross-section in longitudinally spaced relation. The timer 13 has the porcelain body thereof molded so as to provide an elongated groove 33 in the bottom thereof along the front of the timer, the groove being slightly longer than the rib 31 and also of sufficient depth, as indicated in Fig. 8, to permit easily placing the timer 13 on the holder 10 with the rib 31 entered in the groove 33. In like manner the shakers 11 and 12 have the porcelain bodies thereof molded so as to provide grooves 34 and 35 in the bottoms thereof along the front for reception of the ribs 30 and 32, respectively, the grooves being slightly longer than the ribs and also of sufficient depth to make it easy to remove and replace the shakers, although the shakers and timer are held securely enough by the ribs to eliminate likelihood of their accidental displacement from the holder. The retaining ears 24 and 25 cooperate with the ribs 30 and 32, respectively, to prevent the shakers from being upset, and they also facilitate setting the shakers down over the ribs, because once the shaker is engaged with the cooperating ear 24 or 25 the groove in the bottom of the shaker is assured of alignment with the retaining rib on the holder and the housewife has no difficulty in interlocking the shaker with the holder. The shakers 11 and 12 may be interchanged, although the design ornamentation on the shakers is usually such that the salt shaker 12 is on the right and the pepper shaker 11 on the left of the timer. Each of the shakers 11 and 12 has in addition to the bottom grooves 34 and 35 two other grooves 36 and 37 in the back in aligned longitudinally spaced relation so as to provide an intermediate web portion 38. These grooves receive the ribs 30-32 when the shakers are laid on their backs in end to end relationship on the holder, as shown in Figs. 2, 6, and 9, the webs 38 under these conditions lying between the ends of the ribs, as clearly appears in Fig. 9, to prevent endwise displacement of the shakers from the holder. The same pair of shakers 11 and 12 usable in a three-piece set with a timer 13 and arranged to be placed on the holder 10 in the manner shown in Fig. 8 may, therefore, be used alone and placed on the holder in end to end relationship as shown in Fig. 9.

The holder 10 when used on the top of the back rail of a range supports the condiment shakers, or the shakers and timer, quite securely without any danger of any one of these pieces dropping down between the back rail and the kitchen wall. On the other hand, where the range is set with the back rail substantially flush with the wall, the forward spacing of the retaining ears 24 and 25 on the bracket in relation to the attachment lug 26 is of advantage from the standpoint that the shakers are spaced from the wall and can, therefore, be more easily taken hold of and removed and replaced conveniently. The same advantage is gained when the holder is placed on the cooking top; there the desired space relationship is secured between the condi-

ment shakers and the back rail, as should be clear from Fig. 7.

It is believed the foregoing description conveys a good understanding of the objects and advantages of my invention. The appended claims have been drawn to cover all legitimate modifications and adaptations.

I claim:

1. As an article of manufacture, a bracket of the character described comprising a one-piece sheet metal body formed to provide an elongated substantially flat shelf in a substantially horizontal plane, one longitudinal edge portion of which forming the front of the shelf is formed to provide longitudinally spaced but aligned, elongated, article retaining flanges bent upwardly from the body in substantially right angle relationship to the plane of the shelf and bent outwardly and downwardly back to the plane of the body to define flanges on the front of the shelf of substantially C-shaped cross-section to fit in recesses provided in the bottoms of articles seated on the shelf, the other longitudinal edge portion of the shelf forming the back thereof being formed to provide an attaching flange portion in substantially right angle relationship to the plane of the shelf.
2. As an article of manufacture, a bracket of the character described comprising a one-piece sheet metal body formed to provide an elongated substantially flat shelf in a substantially horizontal plane, one longitudinal edge portion of which forming the front of the shelf is formed to provide longitudinally spaced but aligned, elongated, article retaining flanges bent upwardly from the body in substantially right angle relationship to the plane of the shelf and bent outwardly and downwardly back to the plane of the body to define flanges on the front of the shelf of substantially C-shaped cross-section to fit in recesses provided in the bottoms of articles seated on the shelf, the middle portion of the other longitudinal edge portion of the shelf forming the back thereof being formed to provide an attaching flange in substantially right angle relationship to the plane of the shelf, and the opposed end portions of the last named longitudinal edge portion being formed to provide upwardly projecting article retaining flanges in substantially right angle relationship to the plane of the shelf and in substantially parallel relation to the first mentioned flanges and spaced therefrom far enough to accommodate therebetween articles seated on the shelf in interfitting relationship to the first mentioned flanges and in abutment with the front faces of the last mentioned flanges.

3. For use with an article such as a condiment shaker adapted to be demountably supported on a shelf and having a recess provided in the bottom thereof at one edge to receive a flange when the article is placed on the shelf, a shelf member having an upwardly projecting retaining flange provided on one edge thereof for preventing accidental displacement of the article from the shelf while the edge portion of the article seated on the shelf conceals the shelf from view.

4. A holder for cooking range accessories such as condiment shakers adapted to be mounted on top of the back rail or on the cooking top in front of the back rail, said holder consisting of a flat sheet metal body of substantially rectangular form bent downwardly along one longitudinal edge portion to provide an attaching

flange portion, said flange portion having an opening provided therein to receive fastening means for securing the same to the back of the back rail or back of the cooking top when the body is resting on top of the back rail or on the cooking top, the other longitudinal edge portion of said body being bent upwardly and outwardly and downwardly to provide upwardly projecting, longitudinally spaced but aligned, elongated flanges of substantially C-shaped cross-section to fit in recesses provided in the bottoms of articles seated thereon, whereby to prevent accidental displacement thereof from the holder when seated thereon with the recessed bottom portions thereof disposed in interfitting relation with said flanges and concealing said flanges from view.

5. A holder for cooking range accessories such as condiment shakers adapted to be mounted on top of the back rail or on the cooking top in front of the back rail, said holder consisting of a flat sheet metal body of substantially rectangular form bent downwardly along one longitudinal edge portion to provide an attaching flange portion, said flange portion having an opening provided therein to receive fastening means for securing the same to the back of the back rail or back of the cooking top when the body is resting on top of the back rail or on the cooking top, the other longitudinal edge portion of said body being bent upwardly and outwardly and downwardly to provide upwardly projecting, longitudinally spaced but aligned, elongated flanges of substantially C-shaped cross-section to fit in recesses provided in the bottoms of articles seated thereon, whereby to prevent accidental displacement thereof from the holder when seated thereon with the recessed bottom portions thereof disposed in interfitting relation with said flanges and concealing said flanges from view, the first mentioned longitudinal edge portion of said body being further formed to provide upwardly projecting flanges in substantially parallel relation to the last named flanges and in forwardly spaced relation to the attaching flange for engagement with the backs of the articles for support thereof against tipping and against displacement from interfitting engagement with the last mentioned flanges.

6. As an article of manufacture, a one-piece

sheet metal bracket, comprising a generally rectangular body formed to provide intermediate its ends on the opposed longitudinal edge portions a relatively long upwardly projecting article retaining flange and a downwardly projecting attaching flange in substantially parallel relationship, said body being further formed to provide opposed end portions narrower than the intermediate portion and having relatively 10 short upwardly projecting article retaining flanges on the longitudinal edge portion thereof in longitudinal alignment with the first mentioned flange but spaced from the opposite ends thereof, and upwardly projecting article retaining flanges on the other longitudinal edge portion in substantially parallel relation with the last mentioned flanges.

7. An article of manufacture as set forth in claim 6, wherein the first mentioned relatively 20 long flange and the relatively short flanges in longitudinal alignment therewith are bent outwardly and downwardly back to the plane of the body to a substantially C-shaped cross-section, whereby said flanges are adapted to fit in similarly shaped recesses provided in bottoms of articles seated on the body.

8. As an article of manufacture, a one-piece sheet metal bracket, comprising a generally rectangular body formed to provide intermediate 30 its ends on the opposed longitudinal edge portions a relatively long upwardly projecting article retaining flange and a downwardly projecting attaching flange in substantially parallel relationship, the opposite end portions of said 35 body having on one longitudinal edge portion relatively short upwardly projecting article retaining flanges, said flanges being in longitudinal alignment with the first mentioned flange but spaced from the opposite ends thereof, and 40 said end portions having on the other longitudinal edge portion upwardly projecting article retaining flanges in substantially parallel relation with the last mentioned flanges, the first 45 mentioned relatively long flange and the relatively short flanges in longitudinal alignment therewith being bent outwardly and downwardly back to the plane of the body to a substantially C-shaped cross-section, whereby said flanges are 50 adapted to fit in similarly shaped recesses provided in bottoms of articles seated on the body.

HAROLD H. RING.
